CLAIM

We claim the ornamental design for an oral care device and base, as shown and described.

DESCRIPTION

FIG. 1 is a rear, right, perspective view of the claimed design of an oral care device, according to an embodiment; FIG. 2 is a bottom, front, perspective view of the claimed design of FIG. 1; FIG. 3 is a bottom view of the claimed design of FIG. 1; FIG. 4 is a top view of the claimed design of FIG. 1; FIG. 5 is a left side view of the claimed design of FIG. 1; FIG. 6 is a right side view of the claimed design of FIG. 1; and, FIG. 7 is a front side view of the claimed design of FIG. 1.

FIG. 8 is a rear side view of the claimed design of FIG. 1. The broken lines in the drawings illustrate environmental structure and form no part of the claimed design.

1 Claim, 5 Drawing Sheets
